UNITED STATES PATENT OFFICE.

THOMAS THORNE BAKER, OF LONDON, ENGLAND, ASSIGNOR OF ONE-THIRD TO CHARLES HENRY WATSON AND ONE-THIRD TO FREDERICK WILLIAM WATSON BAKER, BOTH OF LONDON, ENGLAND.

APPARATUS FOR TRANSMITTING PICTURES.

Application filed December 10, 1925, Serial No. 74,589, and in Great Britain December 11, 1924.

This invention comprises improvements in and connected with the telegraphic transmission of pictures, diagrams and other impressions, and is connected with methods and apparatus employing synchronized drums at the transmitting and receiving stations, a feed in the direction of the axle of the drum being imparted to the transmitting or receiving element, such as a stylus or illuminant, by means of a screw feed mechanism.

The principal object of this invention is to provide for the anti-frictional mounting of the carriage and feeding by the screw, so that frictional losses or resistance may be minimized as much as possible.

The importance of the anti-frictional mounting of the carriage and feeding by the screw is that it is possible successfully to employ a small clockwork or gramophone type of motor for the driving of the drums, these motors possessing a sufficient power storage capacity for enabling the drums to be driven for a sufficient period of time for the transmission and reception of pictures of reasonable dimensions, given that the said anti-frictional means are employed so that little power is absorbed by the feed. A further object of this invention is to provide an efficient portable and compact construction containing within itself a spring motor, relay apparatus, a drum and carriage, and anti-frictional mounting and screw feed mechanism for such carriage.

According to this invention the transmitting or receiving element is supported by a wheeled carriage running on rails and fitted with a knife edge disc or wheel engaging a fine worm or thread on the axle of the drum. The carriage may comprise a frame fitted with two wheels situated at a distance from one another and adapted for running upon one and the same track rail, these wheels giving two points of support and a third point of support being at the point of contact between the knife edge and the feed screw which is parallel to the said track rail. The carriage is advantageously arranged to tip about the track rail for running it back or for putting it out of the way, a suitable guard being provided to prevent the wheels or rollers escaping from engagement with the rail when the carriage is tipped. The drum and carriage track rail are preferably

mounted upon an elevated base or frame 55 which is supported so as to permit of fixing the spring motor beneath it with the winding spindle extending vertically up through the base. The motor spindle is suitably geared, with the axle of the drum, and any 60 necessary clutches are provided where required.

In this way a self-contained motor-driven apparatus is provided occupying very little space and capable of being carried about 65 with ease, this apparatus nevertheless being adapted for the reproduction of pictures of reasonable dimensions which are telegraphically transmitted according to the known principle of sending a succession of signals 70 by the aid of a picture on a synchronous transmitting drum.

In order to enable the invention to be readily understood, reference is made to the accompanying drawings illustrating one 75 suitable construction by way of example, in which drawings:—

Figure 1 is a perspective view of the drum with the improved carriage mounting and feed, these parts being mounted on a plate 80 supported by a case containing the spring motor and relay.

Figure 2 is a side elevation of the complete apparatus removed from the said case, and

Figure 3 is a transverse section taken up on the line 3—3 of Figure 2.

In the drawings, *a* is a plate or frame upon which is a bracket *b* and a combined bracket and housing *c*. The parts *b* and *c* are fitted with bearings for the axle of the drum *d* and the bracket *b* also serves for supporting a rail *e*, the opposite end of the latter being supported in a pillar *f*. The axle of the drum *d* comprises a plain part *d'* 90 and a part *d''* threaded with a very fine pitch screw for the feeding of a carriage supporting the transmitting or receiving and recording element which, in the example illustrated is a stylus *g*. The carriage aforesaid comprises a bar *h* fitted with two grooved track wheels or rollers *j* disposed for running on one and the same track rail *e*, and a transverse arm or part *k* having its free end bifurcated and fitted with bearings for the 100 axle of a knife edge disc *l*. As will be seen from Figure 1 the track wheels *j* are disposed so that there is a relatively long wheel

base on the track rail e , and the arm k is of such a length that the knife edge disc l engages the fine screw thread on the axle part d^2 when the carriage is in the working position seen in Figure 1. The axles of the track wheels j may run in ball or roller bearings and the knife edge disc l may be mounted to run between centres so as to reduce the friction to a minimum. Also, the knife edge disc l may be mounted with a slight inclination so that it runs nicely in the fine screw thread and has no tendency to mount the thread.

At the opposite end of the carriage to that at which the arm k is situated, there is fixedly mounted a transverse arm m fitted with a weight n . The stylus g is secured in a holder on a small lever o which is influenced by a spring p . Thus, the weight n keeps the arm m down in a horizontal position and imposes an appropriate load on the knife edge disc l to keep it in proper engagement with the feed screw d^2 and the spring p keeps the stylus g lightly but firmly pressing down upon the drum d .

It will now be understood that if the drum d is revolved, the screw threaded axle part d^2 will operate the knife edge disc l so as to feed the wheeled carriage along the track rail a and thereby carry the stylus g along the drum d from right to left of Figure 1. When the carriage is to be returned, or when for any reason, it is desired to have the stylus g out of the way the carriage is tilted about the rail e as fulcrum to the dotted line position in Figure 3, thereby removing the stylus g from the drum d and the knife edge disc l from the screw threaded axle part d^2 .

At the rear of the carriage there is a projection q carrying a normally horizontal pin r which takes just beneath the track rail e and prevents the grooved wheels j escaping from the track. A pillar s on the base plate a supports a horizontal guard t and it will be seen from the dotted line positions in Figure 3 that this guard t is engaged by the pin r when the carriage is tipped over the vertical dead centre, so that the weight is beyond the pivotal axis. Thus the carriage will remain in the dotted line position until it is turned down to the full line position when required for use.

On the plain part d' of the axle there is fixed a pulley u which is driven through a belt v by the pulley w of the spring motor x of the gramophone type. The motor x is fixed beneath the base plate a so that its winding spindle y is vertical and extends upwards through the base plate, its upper end being thus accessible for application of a winding key. Beneath the base plate a there is also fixed the polarized relay device y' of known type. The base plate a is supported upon pillars or standards z of a suitable height. This complete apparatus is readily inserted

into or removed from the case seen in Figure 1, in which it is protected and is readily transportable with convenience and safety.

When the apparatus is to be used, the spring motor is wound up, and at the sending station a prepared picture or diagram is placed around the drum d . At the receiving station a sheet of prepared paper is placed on the drum which is connected up as one pole in a local circuit which includes the stylus. At a given signal, the drums having been set in revolution, the sender and receiver lower the carriages of their respective machines so as to bring the knife edge wheels on to the feed screws and the transmitting stylus or device and the receiving stylus on to their respective drums. The sending station apparatus then transmits a varying line current which passes from stylus g to drum d through the paper, the latter carrying a preparation which is electrolyzed by the passage of the current. The electrolyzing of the preparation produces marks of varying intensity which result in the composition of a picture in known manner.

It is essential to synchronize the drums at the sending and receiving stations, and for this purpose each is timed to revolve approximately once in two seconds, for example. On the transmission drum axle there is a cam which, at each revolution makes a contact for sending a reverse line current for operatively affecting the polarized relay y' of the receiving station apparatus. The latter, as shown on the drawing, comprises an arm 1 on the drum axle, which arm is arrested at each revolution by a stop 2 on an armature 3 of an electro-magnet 4 which is energized under control of the relay y' . The arm 1, in approaching the stop 2 presses back a spring catch 5. When the arm 1 is against the stop 2 which prevents further forward motion, the catch 5 springs out behind the arm 1 and prevents any rebound. However, the engagement of the arm 1 with the spring catch 5 may also close a gap in the reverse current relay circuit so that the latter can be energized only when the arm 1 is in or approaching the stop position. The belt v slips on its pulley when the drum is arrested, or suitable friction clutches may be provided. For example the pulley u may be carried by a sleeve 7 slidably fitted upon the drum axle part d' and pressed against a collar 9 on such axle part by a spring 8 arranged between the pulley u and a collar 9 adjustably fixed on the spindle part. Thus, if the receiving drum be set to revolve at a slightly quicker speed than the sending drum, it will be momentarily arrested at the completion of each revolution. Immediately after the arrest, however, the cam of the sending drum makes the aforesaid circuit contact so that the relay y' is influenced by a reverse line current. There-

upon, the relay y' brings about the energization of the magnet 4 which attracts its armature and removes the stop 2 from the path of the arm 1 which, with the drum d , therefore resumes its revolution. In practice, the receiving drum is set to perform each revolution in a fraction of a second less than the transmitting drum and is capable of being adjusted by the speed controller at 6 to such a nicety that it is hardly arrested at the completion of each revolution owing to the fact that the transmitting drum makes the release contact practically simultaneously with the arrival of the arm 1 at the stop 2 of the receiving instrument or instruments. The feed screw d^2 aforesaid, instead of being on an extension of the drum axle, may be on a separate spindle geared with the drum d , if this arrangement is preferred for some constructions.

It is to be understood that although a receiving instrument with a stylus is adapted for recording by having an electrolytic action on prepared paper in known manner, the carriage of the receiving element may support other recording devices such as a lamp having its rays directed or focused on to a spot on a sheet of sensitized paper wrapped around the drum. In this case the transmitting apparatus may comprise a light-sensitive cell acted upon by rays of light after passing through the image of the picture to be telegraphed. All such devices in transmitting or receiving apparatus may be generically referred to as telegraphic tracers, as they may be said to trace a line over the picture during the revolution of the drum and feed of the carriage.

It is further to be understood that although the machine of these improvements has been described in connection with line telegraphy, it may also be adapted for working successfully in connection with the radio telegraphic transmission of pictures. Indeed, in contemplating the broadcasting of phototelegrams by wireless, it is of great importance that the apparatus should operate as efficiently as possible and that it should be possible for the drum to make sufficient revolutions under the drive of its spring motor for enabling the size of picture for which it has been designed to be reproduced by the power stored in one winding operation.

It may be advantageous to substitute worm gearing for the belt gear in which case the most convenient arrangement of the motor may necessitate the extension of the winding spindle through a side or end of the case. Also, instead of a friction clutch, it may be desirable to substitute a positive clutch under automatic control, this clutch being opened at the moment of arrest and closed at the moment of release of the drum.

65 I claim:—

1. Apparatus for use in telegraphing pictures, diagrams, and the like, comprising a revoluble drum adapted for supporting a picture sheet, a wheeled carriage, a telegraphy tracer device supported on said carriage and adapted for extending over said drum, a carriage track parallel with the axis of said drum, a feed screw revoluble with said drum, and a revoluble knife edge disc supported on said carriage and adapted for engaging said feed screw substantially as set forth. 70

2. Apparatus for use in telegraphing pictures, diagrams and the like, comprising a revoluble drum adapted for supporting a picture sheet, a wheeled carriage comprising wheels one behind the other for tracking a single rail, a telegraphy tracer device supported on said carriage and adapted for extending over said drum, a feed screw revoluble with said drum, a single track rail parallel with the axis of said drum, and a revoluble knife edge disc supported on said carriage and adapted for engaging with said feed screw for feed of said carriage and also for forming with said wheels a triangulated support for said carriage substantially as set forth. 85

3. Apparatus for use in telegraphing pictures, diagrams, and the like comprising in combination a revoluble drum adapted for supporting a picture sheet, a wheeled carriage having its wheels arranged one behind the other for running on a single track rail, a telegraphy tracer device supported on said carriage and adapted for extending over said drum, a single track rail parallel with the axis of said drum, said rail being adapted for serving as a fulcrum about which said carriage can be raised and lowered so that its wheels act as a pivot bearing on said fulcrum, a feed screw revoluble with said drum, a knife edge disc supported on said carriage and adapted for resting upon said feed screw and engaging the thread thereof, and a weighted arm on said carriage for appropriately adjusting the pressure of said disc on said screw substantially as set forth. 90 100

4. Apparatus for use in telegraphing pictures, diagrams, and the like comprising in combination, a revoluble drum adapted for supporting a picture sheet, a carriage fitted with single track grooved wheels, a telegraphy tracer device supported on said carriage and adapted for extending over said drum, a single track rail parallel with the axis of said drum and adapted for serving as a fulcrum to said wheels when said carriage is lifted or lowered on said wheels as pivot bearings, a feed screw revoluble with said drum, a knife edge disc supported on said carriage and adapted for engaging said feed screw, and guard means for preventing said carriage wheels from disengaging from 110 120 125 130

the track rail when said carriage is tilted about said track rail as fulcrum substantially as set forth.

5. In apparatus for use in telegraphing pictures, said apparatus being of the revolving drum type with carriage operated by feed screw revolving with said drum, a single track rail in parallelism with said drum, a carriage comprising a longitudinal member fitted with aligned wheels for running on said track and two laterally extending members, one of the latter being fitted with anti-frictional means in operative engagement with the feed screw and the other being hingedly mounted and fitted with a loading weight and with a telegraphic tracer device, and self-contained motive power means in releasable driving engagement with said drum substantially as set forth.
- 10 6. In apparatus for use in telegraphing pictures, said apparatus being of the revol-
luble drum type with carriage operated by

feed screw revolving with said drum, an antifrictional support and feed means for said carriage comprising track wheels and a revoluble knife edge disc engaged with said screw by lowering said carriage about its track wheels as pivot bearings, and an adjustable loading on said carriage operative for maintaining appropriate feed engagement between said disc and screw substantially as set forth.

7. In an apparatus of the character described, a rotary drum, a tracer device movably mounted in operative relation to the drum, a support for the tracer device, a feed screw rotatable with the drum, a rotatable knife-edge disc engaging said screw, and means connecting the disc and support whereby the movement of the disc longitudinally of the screw imparts movement to the tracer device longitudinally of the drum.

THOMAS THORNE BAKER.
